UNITED STATES PATENT OFFICE.

FINLAY R. PORTER, OF SOUTHAMPTON, NEW YORK.

COMBINED DRIVE-WELL AND PUMP.

SPECIFICATION forming part of Letters Patent No. 544,376, dated August 13, 1895.

Application filed June 8, 1894. Serial No. 513,864. (No model.)

To all whom it may concern:

Be it known that I, FINLAY R. PORTER, a citizen of the United States, and a resident of Southampton, in the county of Suffolk and State of New York, have invented certain new and useful Improvements in a Combined Drive-Well and Pump, of which the following is a specification.

This invention relates to devices for sinking wells, particularly where the water or other liquid which it is desired to reach is a considerable distance below the surface of the ground, the object of the invention being to provide a simple, cheap, and readily-operative device by means of which, after the water has been reached, the final section of the driven well may be converted into a permanent pump.

The invention consists in the novel construction, combination, and arrangement of parts hereinafter fully described.

In the accompanying drawings, forming part of this specification, in which like letters of reference designate corresponding parts throughout, Figure 1 is a vertical section taken through the center of a device embodying my invention when ready for use. Fig. 2 is a section, taken upon similar lines, of the inner cylinder, forming part thereof, having connected thereto the inserting and removing pipe which I use in connection with the device. Fig. 3 is a horizontal transverse section taken upon the line xx , Fig. 1. Fig. 4 is a side elevation of a device used for removing the ball-valve inserted in the well.

In sinking wells to a considerable depth it has been the custom to employ a hollow cylindrical shaft commonly termed a "point," and it is to such class of well-driving devices that the invention more particularly appertains.

In the practice of my invention I secure upon the usual drive shaft or point A, surrounding the upper end thereof, a joint or coupling B, which said coupling may be secured to the said drive shaft or point by any desired means and is interiorly screw-threaded at the top. The said coupling has at the center thereof an inner annular flange C, which is also screw-threaded. Within the flange C is inserted a metallic cylinder D, preferably constructed of brass and tapering or decreased in diameter at its lower end D',

which latter is exteriorly screw-threaded to engage with the flange C. Surrounding this cylinder is a casing E, also screw-threaded at 55 the lower end and inserted in the top of the coupling B. This having been effected, the point A is sunk into the ground by any desired means in any approved manner until water has been reached, whereupon a preferably solid brass ball F is dropped from above into the casing E, whence it falls into the cylinder D, the lower reduced portion D' thereof forming a seat for the said ball, into which seat the said ball will find its way. As soon 60 as the ball has been deposited in the cylinder a plunger G is inserted therein, the said plunger being of the usual or of any other preferred construction and having screwed in the top thereof a tubular handle H, which I 70 prefer to form of a number of small pipe-sections H', the length of the plunger being adjusted by screwing together more or less of the pipe-sections, according to the depth to which the well is sunk. Any suitable bearings may 75 be arranged upon the top of the casing E for the rod H to work in, and thus constructed the device forms a perfect well-pump, the ball F serving as a valve.

I claim it as an advantage of my invention 80 that the last section of the drive well or pipe as thus formed may at once be transformed into a pump by the mere dropping of the ball-valve therein and insertion of the plunger, as by this means a saving of at least fifty per 85 cent. of the cost of construction of devices of this character and the sinking of wells thereby is effected.

In order that the cylinder D may be removed from engagement with the inner flange 90 C of the coupling B, I form upon the interior periphery of the said cylinder, at its lower end D', a left-handed screw-thread D², into which a tubular rod or pipe I may be screwed, whereby after the said pipe has been turned 95 as far as the depth of the thread will permit any further turning thereof will unscrew the lower end of the cylinder, which may then be drawn upward by means of the said rod or pipe I. Not only is this arrangement advantageous in removing the cylinder after the well is driven, should such be desired, but also by this means the well may be completely driven before the cylinder is inserted in the

coupling, this insertion being effected by means of the said rod I; and, furthermore, should it be desired to repair the well at any time it will be of especial benefit to provide for the removal of the said cylinder, though, of course, the plunger G and the ball-valve F would in that case require first to be removed. The said ball-valve is preferably removed by means of the device shown in Fig. 4, which comprises a rod J, having curved metallic spring-arms J', which, when pressed downwardly upon the ball between the same and the sides of the cylinder D, engage said ball and clasp the same.

Having thus fully described my invention, what I claim as new, and desire to secure by Letters Patent, is—

1. In a combined drive well and pump, the combination, with a suitable driving shaft 20 or point, of a coupling secured thereon and screw-threaded at the top, a pipe section engaging therewith, a cylinder within the pipe removably secured to the coupling and reduced in diameter at the lower end, a ball 25 adapted to fit within the said end when

dropped in the cylinder, and a plunger adapted to be inserted therein, substantially as shown and described.

2. In a combined drive well and pump, the combination, with a driving shaft or point, 30 of a coupling secured thereon, and screw-threaded at the top, a pipe section engaging therewith, an annular screw-threaded flange at the inner side of the coupling, a cylinder within the pipe having a reduced lower end 35 to form a valve seat and screw-threaded to engage with the flange, a reversed screw-thread formed upon the interior of the cylinder, a solid ball adapted to fit within the lower end of the cylinder, and a plunger 40 adapted to be inserted in the said cylinder, substantially as shown and described.

In testimony that I claim the foregoing as my invention I have signed my name, in presence of two witnesses, this 21st day of May, 45 1894.

FINLAY R. PORTER.
